UNITED STATES PATENT OFFICE.

HAZEL H. ADLER, OF NEW YORK, N. Y.

DESIGN FOR A TEXTILE-EXHIBITING DEVICE.

Application filed November 19, 1925. Serial No. 15,468. Term of patent 14 years.

To all whom it may concern:

Be it known that I, HAZEL H. ADLER, a citizen of the United States, residing in the city of New York, county of New York, and State of New York, have invented a new, original, and ornamental Design of a Textile-Exhibiting Device, of which the following is a specification, reference being had to the accompanying drawing, forming part thereof.

The figure is a face view of a textile exhibiting device in which pieces of the textile goods are arranged so as to radiate from a central disc and between bars radially extending from the disc to a pair of concentric contrasting bands, one near the outer ends

of the bars and one lying between that band and the central disc. The pieces of textile goods have overlapping or loose folds generally radial as shown. In addition to the wheel-like form produced by the central disc, radial bars and concentric contrasting bands, supporting figures are provided at each side of the wheel. The article is substantially flat, its cross section being due to the thickness of the disc, bars and bands supporting the folded textile goods, plus the slight projections of the folds of the goods.

I claim:

The ornamental design for a textile-exhibiting device as shown and described.

HAZEL H. ADLER.
